UNITED STATES PATENT OFFICE.

JAMES T. BRUNDAGE, OF NIAGARA FALLS, NEW YORK.

DESIGN FOR A FAN.

Specification forming part of Design No. **6,774**, dated July 15, 1873; application filed June 18, 1873.

To all whom it may concern:

Be it known that I, JAMES T. BRUNDAGE, of Niagara Falls, in the county of Niagara and State of New York, have invented a Design for Faus, of which the following is a specification:

My design relates to that class of stiff fans in which the body is composed of feathers and surrounded or bound with down; and the design consists of this kind of fan having one of its faces covered with paper, wood, or other material, so as to present a smooth plain surface, which can be ornamented with photographic or other pictures, if desired.

In the accompanying drawing, Figures 1 and 2 are face views representing, respectively, the feathers of the one side and the smooth surface of the opposite side.

Like letters of reference designate like parts in each of the figures.

A is the handle; B, the border of down; C, the feathers composing one face; and C', the plain smooth surface forming the other face of the fan. The smooth face C' may be left plain or be painted in any desired color, or it may be ornamented with photographic or other suitable pictures, as shown in the drawing, Fig. 1, in which a view of Niagara Falls is represented.

I am aware that stiff fans, as well as folding fans, have been ornamented with pictures in a variety of ways, and this I do not claim.

What I claim as my invention is—

A design for a fan, substantially as herein shown and described.

JAMES T. BRUNDAGE.
